SPRAY GUN

Filed Feb. 8, 1929

Philip S. Case, INVENTOR,

BY

Byrnes, Townsend & Richenstein, ATTORNEYS.

UNITED STATES PATENT OFFICE

PHILIP S. CASE, OF NIAGARA FALLS, NEW YORK, ASSIGNOR TO ELECTRO METALLURGICAL COMPANY, A CORPORATION OF WEST VIRGINIA

SPRAY GUN

Application filed February 8, 1929. Serial No. 338,586.

My invention relates to spraying devices for producing a spray of solids in suspension with a gas and especially to the production of a spray which may be projected at a low velocity and which may be homogeneously mixed with a liquid binding material.

A low velocity moist spray is useful for producing a binder moistened coating of powdered solids upon fragile objects such as sand casting molds. The device may be used to produce a low velocity spray of dry solids. A dry spray is useful to absorb an excess of binder on the surface of a binder moistened coating or for other purposes.

15 Therefore it is among the main objects of my invention to provide devices for producing a low velocity spray of solids and gas.

Another object of my invention is to provide a device which will homogeneously impregnate a low velocity spray of solids and gas with a liquid.

25 Other objects of my invention will appear in connection with the description of the spray gun embodying my invention which is shown in the accompanying drawing, in which:

30 Figure 1 is a view of a spray gun shown partially in section and partially in elevation,

Figure 2 is a side elevational view of the air distributing ring,

Figure 3 is a cross sectional view of the air distributing ring taken along the line III—III of Figure 2,

Figure 4 is a side elevational view of the emulsifier ring,

Figure 5 is a cross sectional view of the emulsifier ring taken along the line V—V of Figure 4,

Figure 6 is a side elevational view of the nipple member,

Figure 7 is an end elevational view of the nipple member, and

Figure 8 is a cross sectional view of the nipple member taken along the line VIII—VIII of Figure 7.

The spray gun may consist of a handle portion and a head portion or barrel. The handle portion may consist of a series of pipes or passage means which provide a pas-

sage 1 for solids and air, a passage 2 for a mixture of liquid and air and a passage 3 for air. The passages or conduits through the handle lead to corresponding passages or bores in the head portion. The handle may consist of a central pipe 5 carrying a bracket 6 and side pipes which are carried by the bracket and supported at the ends in a perforated plate 8. The head or barrel portion may be screwed to the plate 8 by a plurality of screws in such a way that the passage way will be continuous through the plate and head.

In the barrel or head of the gun the mixture of solids and air are discharged from a central port which is the terminus of the passage 1. The liquid and air mixture is conducted through the passage 2 and an emulsifier and is discharged through a series of ports 10 which cause the atomized liquid to surround the atomized solids. The air is conducted through an air shut off and regulating valve 7, the passage 3 and an equalizer into the head and is discharged through the ports 11 into the stream of solids and air so as to agitate the mixture. By reason of this agitation and of the disposition of the projected mixtures with respect to each other, the mixtures and the air combine external of the gun and form a spray of suspended solids which are thoroughly and homogeneously impregnated with the liquid.

The solids are supplied to the gun as a stream or cloud of solids suspended in air. This suspension of atomized solids may be produced by any suitable means external of the gun provided the suspension is homogeneous and the velocity of the stream is suitable for the purpose intended. This mixture is usually conducted to the gun through a flexible hose 12 which discharges into the central pipe 5. In order to prevent rapid erosion of the metal of the pipe a resilient lining 13 may be provided by inserting a gum rubber hose snugly in the passage 1 and extending it to the exit port in the head. The lining may be secured by inserting a tapered ring 14 into the end of the hose and then screwing down the reducer 15 so that the hose 100

will be wedged between the head of the pipe. 5 and the ring 14.

The air and liquid mixer, preferably although not necessarily constitutes a part of 6 the gun. I prefer to embody the mixer in the handle of the gun since frequent regulation of the air and liquid supplied may be 10 needed. Air is supplied to the mixer from a suitable source through the branch 16 and liquid is supplied under pressure through the branch 17. Valves 18 and 19 in the branches 15 16 and 17 are used to vary the mixture of liquid and air and to discontinue the mixture when it is not needed. The branch pipes 20 16 and 17 are disposed at an angle of about 30° from each other and at the point of union of the pipes a comparatively large amount of air is usually mixed with a small amount of liquid. The liquid is then carried by the air 25 through the passage 2 into the emulsifier which is contained in the gun head.

A reduced portion cuts across the passage 2 near the end of the gun head and the emulsifier is mounted upon this reduced portion. 25 Another reduced portion cutting the passage 3 is formed near the end of the gun head and a gas equalizer is mounted on this portion. The latter reduced portion is threaded so as to screw on a recessed nipple 20 which is so 30 recessed as to provide chambers and passages. The unreduced portion of the head is threaded and the cap 21 is screwed on. The cap extends over the extremity of the nipple member and acts as a stop or lock therefor. 35 The cap encloses the nipple member 20 and forms the outside walls of the air equalizing chamber.

The emulsifier chamber 22 is formed within the inner recessed portion of the nipple member 20 and the reduced end portion 23 of the gun head. A ring 24, having grooves 25 extending to the outer edges of the ring, is 40 slidably mounted in the chamber 22 and is cut to a size so as to provide a narrow annular passage 26 between the outer margin of the ring and the inner threaded surface of the nipple member. The ring 24 is provided with radial or other inclined grooves 25 extending from its inner to its outer edges. When the 45 mixture of liquid and air is passed from the passage 2 through the chamber 27 and around the ring, the tortuous and restricted path formed by the grooved ring causes a violent mixing or emulsifying of the liquid and air. 50 The ring 24 may be grooved on both sides if desired but grooving on the side which comes in contact with the nipple member is all that is necessary. When grooves are provided on both sides of the ring the grooves may be 55 staggered as shown in Figure 5. The staggering of the grooves in the ring provides a spiral path for the liquid passing around the notched edges of the ring. I prefer to groove the ring on both sides if for no other 60 reason than to insure proper mounting of 65

the ring. An annular groove 28 around the face of the reduced section of the gun head may be made to provide a preliminary distributing chamber and an annular passage 70 around the barrel. The innermost bore 30 of the ring 24 is preferably given a sliding fit on the reduced end section of the gun head.

Discharge ports 10 are formed between the gun head and the nipple member. I may form the ports 10 in the nipple member by 75 cutting longitudinal grooves therein as shown in Figures 7 and 8 but the grooves may be formed in the outer surface of the reduced portion of the barrel and they may be disposed spirally if so desired. At all events, the ports 10 are arranged so that the projected atomized mixture of liquid and air will form a cylindrical envelope around the discharged mixture of solids and air. In order to prevent a divergently directed envelope of liquid and air, a shallow annular groove 32 having an arcuate cross section is cut near the end of the barrel. As the mixture of liquid and air flows from the edge of this groove it is impelled slightly toward the axis of the 80 barrel.

The air passage 3 is cut across by a second reduced portion of the head and an annular groove 35 is formed in the face of the cut so as to provide an annular passage through 85 which the air from the passage 3 may be distributed. A distributing ring 36 is screwed on the reduced portion of the barrel so as to form the front wall of the annular passage 35 and the rear wall of an intermediate distributing chamber 37. Spaced ports 38 are formed in the ring so as to distribute the air approximately equally in the intermediate chamber 37. The ports 38 may consist of 90 equally spaced perforations in the ring 36 105 but better distribution results when one portion of the ring 36 is left unperforated and the unperforated portion is spaced as a baffle directly in front of the air passage 3. An unperforated portion 39 subtending an angle of 110 about 30° at the center of the ring has given good results but the baffle may be of greater or less extent. In order to give the most effective distribution of air around the annular groove 35, the ring is made to fit snugly 115 against the face cut in the barrel and the cap 21. The ring is threaded internally so that it may be screwed snugly on the barrel. The inner end of the nipple member 20 is given a bevel 40 so as to form an enlargement in the chamber 37 in front of the ring 36 and to provide an inclined surface upon which the jets of air from the ports 38 will impinge and effect a further distribution of air.

The largest external cylindrical portion of the nipple member 20 is given a sliding fit in the cap 21 and equally spaced passages 41 are extended from the intermediate chamber 37 to an annular outer or discharge chamber 42. 120 125 130

The passages may be formed by the grooves 41 in the surface of the nipple member.

The grooves 41 redistribute and equalize the air still further and they are preferably disposed spirally so as to swirl the air in the chamber 42 and cause it to cut across the small ports 11 which are spaced near the end of the nipple member and are directed at an angle to the stream of mixed solids and air.

10 The ports 11 are preferably directed radially in a plane perpendicular to the axis of the head so that a curtain of air will be produced through which solids will pass and by means of which they will be violently agitated. The 15 ports 11 may be inclined obliquely to the axis of the head but better spraying results are generally obtained with the ports directed perpendicularly to the axis. Some variation in the inclination of the jets of air may be obtained by adjusting the nipple member 20 out or in so that the air will impinge more or less against the end surface 44 of the head. The ports 11 are situated in a portion of the nipple member which extends beyond the end 25 of the barrel. The nipple is proportioned so that it can be screwed outwardly or inwardly and produce impingement or restriction of the jets discharged from the ports 11. The nipple is held or locked in the adjusted 30 position by screwing down the cap 21 so that it will bear against the end surface 43 of the nipple member.

The above described spray gun finds its principal use in applications which require 35 a low velocity spray of solids or of moistened solids, but it is evident that higher velocities may be used. As a general rule, the mixture of solids and air of the desired consistency is produced at the nozzle and then the liquid 40 and air mixture and the air are adjusted to give the wetness and character of spray desired. A dry spray of mixed powder and air is sometimes desired. Such a spray may be produced by closing the valves 18 and 19.

45 Although I have described one specific embodiment of my invention it is evident that various modifications of my device may be made within the scope of my invention. Therefore, I wish to be limited only by the 50 prior art and by the invention as defined in the appended claims.

I claim as my invention:

1. A spray gun comprising means to form a mixture of liquid and gas, a handle portion having a conduit for conducting a mixture of solids and gas and a conduit for conducting gas, a head portion having passages coextensive with said conduits, a discharge port for the solids and gas and a plurality 55 of annularly disposed discharge ports for gas, said head having a passage for conducting said mixture of liquid and gas and discharge means therefor, means in said liquid and gas mixture passage to intimately mix 60 the liquid and gas and to distribute the mix-

ture equally to the annularly disposed discharge means and means in said gas passage to distribute gas equally to the plurality of annularly disposed discharge ports, said passage for solids and gas being disposed axially in said head and said discharge for the gas and the mixture of liquid and gas being arranged to discharge the same in the vicinity of the discharged mixture of solids and gas so as to form a mixture externally of the head. 75

2. A spray gun comprising a head having a bore for conducting a mixture of solids and gas, a bore for conducting a mixture of liquid and gas and a bore for conducting gas, a cap on the head and a recessed nipple member on the head forming with the cap an intermediate gas chamber, a discharge gas chamber and a communication between the chambers, said nipple member having discharge orifices communicating with the discharge chamber. 85

3. A spray gun comprising a head having a central bore for conducting a mixture of solids and gas, a bore for conducting a mixture of liquid and gas and a bore for conducting gas, a reduced end portion in the head cutting across said bore for liquid and gas, a recessed nipple member on the head forming a liquid and gas chamber communicating with one of said bores, means in said chamber to form a tortuous passage in the chamber, said reduced portion of the head being adapted to slide into the nipple member, said nipple member and reduced portion forming a discharge means communicating with the liquid and gas chamber. 95

4. A spray gun comprising a head having a bore for conducting a mixture of solids and gas, a bore for conducting a mixture of liquid and gas and a gas passage, a cap on the head, a recessed nipple member forming with the cap an intermediate gas chamber and a discharge gas chamber and a ring secured in the intermediate chamber, said head having an annular passage communicating with the gas passage, said ring having passages communicating with the annular passage and the intermediate chamber, and said recessed nipple member having passages extending between the chambers. 110 115

5. A spray gun comprising a head having a bore for conducting a mixture of solids and gas, a bore for conducting a mixture of liquid and gas and a gas passage, a cap on the head, a recessed nipple member forming with the cap an intermediate chamber, a discharge chamber and a communication between said chambers, a perforated ring in the intermediate chamber having an unperforated portion opposite the end of said gas passage, said head having an annular groove communicating with the gas passage and with said perforations. 125

6. A spray gun comprising a barrel mem-

ber having a central axially disposed bore for conducting a mixture of solids and gas, a bore for conducting a mixture of liquid and gas and a bore for conducting gas, a cap on the barrel and a recessed nipple member forming with the cap a discharge gas chamber, said nipple member extending beyond said barrel and having spaced orifices in the extension communicating with the discharge gas chamber, and arranged to discharge gas into the solid-air mixture external of the head.

7. A spray gun comprising a barrel member having a central axially disposed bore for conducting a mixture of solids and gas, a bore for conducting a mixture of liquid and gas and a bore for conducting gas, a cap on the barrel and a recessed nipple member forming with the cap a discharge gas chamber, said nipple member extending beyond said barrel and having a plurality of equally spaced orifices communicating with the discharge chamber and arranged to discharge gas into the solid-gas mixture external of the barrel and at an angle to the direction of flow of the solid-air mixture.

8. A spray gun comprising a head having a centrally disposed conduit for a mixture of solids and gas, a bore for conducting gas and a bore for conducting a mixture of liquid and gas, said head having reduced sections cutting across said bores, a recessed nipple member secured to one of said reduced sections and an outer cap on the head engaging the nipple member and forming a lock therefor, said nipple member having an inner recessed portion and grooves in an inner face thereof which form a chamber and exit ports between the nipple member and the head, outer recesses and grooves in the nipple member which form gas passages and chambers between the nipple member and cap, and openings in the nipple member which communicate with one of the gas chambers and form gas discharge ports.

9. A spray gun comprising a head having a centrally disposed port for discharging a mixture of solids and gas, a gas bore, discharge ports for gas and a bore for conducting a mixture of liquid and gas, said head having a reduced end portion which comprises a face cutting across the liquid-gas bore, another reduced portion of the head cutting across the gas bore, a nipple member having a face in sliding engagement with the reduced end portion of the head and an inner recess in the nipple member in adjustable engagement with said other reduced portion of the head, said recessed portion of the nipple member and the end reduced portion of the head forming a chamber around the head in communication with the liquid-gas bore, the end portion of the nipple member and said reduced end portion of the nipple member forming a discharge means for liquid and

gas mixture between the nipple member and the head.

10. A spray gun comprising a head having a centrally disposed port for discharging a mixture of solids and gas, a gas bore, discharge ports for gas and a bore for conducting a mixture of liquid and gas, said head having a reduced end portion which comprises a face cutting across the liquid-gas bore, another reduced portion of the head cutting across the gas bore, a bored nipple member having an inner grooved face in sliding engagement with the said reduced end portion of the head and an inner recess having an adjustable engagement with said other reduced portion of the head, said recessed portion of the nipple member and other reduced portion of the head forming a chamber around the head in communication with said liquid-gas bore and the grooved face of said nipple member forming discharge ports for liquid and gas mixture between the nipple member and the head.

11. A spray gun comprising a handle portion carrying a liquid and gas mixer, a conduit for gas, a conduit for a mixture of liquid and gas and a conduit for a mixture of solids and gas, a head portion having bores coextensive with the conduits of the handle and a centrally disposed port for discharging the solid and gas mixture, an obstruction in the liquid-gas bore whereby the direction of flow of the liquid and gas is changed so as to intersperse one into the other, and an end portion of the head having ports spaced therearound and in communication with the liquid-gas bore for discharging the mixture of interspersed liquid and gas.

12. A spray gun comprising a handle portion carrying a liquid and gas mixer, a conduit for gas, a conduit for a mixture of liquid and gas and a conduit for a mixture of solids and gas, a head portion having bores coextensive with the conduits of the handle and a centrally disposed port for discharging the solid and gas mixture, an obstruction in the liquid-gas conduit whereby the direction of flow of the liquid and gas is changed so as to intersperse one into the other and obstructions and chambers in the gas conduit to equally distribute gas annularly in the head.

13. A spray gun comprising a handle portion carrying a liquid and gas mixer, a conduit for gas, a conduit for liquid and gas mixture and a conduit for a mixture of solids and gas, a head portion having bores coextensive with the conduits of the handle and a centrally disposed port for discharging solid and gas mixture, an annularly disposed distributor in the gas conduit within the head to equalize the gas and an end portion on said head having liquid-gas discharge orifices spaced therearound.

14. A spray gun comprising a head having a port for discharging a mixture of solids

and gas, a cap on the head, a nipple member on the head recessed so as to form within the cap an outer gas chamber, an inner gas chamber and a communication between the chambers, an air distributing member on the head having spaced ports communicating with a supply of gas under pressure and with said inner chamber, said nipple member having gas discharge ports communicating with the outer chamber and directed so as to project converging currents of gas into the discharged mixture of solids and gas.

15. A spray gun comprising a head having a port for discharging a mixture of solids and gas, a cap on the head, a nipple member on the head recessed so as to form an outer gas chamber and an inner gas chamber within the cap, said nipple member having grooves in the outer surface which form communications between said chambers, a ring on the head having spaced openings therein which communicate with a source of gas under pressure and with the inner chamber, said nipple member having discharge ports communicating with the outer chamber and directed so as to project converging currents of gas into the discharged mixture of solids and gas.

16. A spray gun comprising a barrel member having a central port for discharging a mixture of solids and gas, a gas passage, a cap on the barrel, a nipple member projecting beyond the barrel, said nipple member being recessed so as to form an end chamber and having gas discharge ports in the projecting portion which communicate with the end chamber, said barrel having a reduced portion which forms an equalizing chamber with the cap and nipple member, a gas equalizer on said reduced portion having ports communicating with the gas passage and with the equalizing chamber, means in said reduced portion to adjust the nipple member so as to move the discharge ports out or in with respect to the end of the barrel and means on the cap to lock the nipple member in its adjusted position.

17. A spray gun comprising a head having a centrally disposed port for discharging a spray of solids and gas and a bore for conducting gas, said head having a reduced section which forms a face cutting across the gas conducting bore, the face being channeled to form a passage around the head which communicates with the bore, a ring on the reduced section bearing against said face, a recessed nipple member on said reduced section capable of being adjusted inwardly and outwardly on the head and a cap on the head engaging the end of said nipple member so as to lock the same in its adjusted position and to form inner and outer chambers and passages between the chambers said ring forming one wall of the inner chamber and having a communication between said channel and inner chamber.

18. A spray gun comprising a head having a centrally disposed port for discharging a spray of solids and gas and a bore for conducting gas, said head having a reduced section which forms a face cutting across the gas conducting bore, the face being channeled to form a passage around the head which communicates with the bore, a ring on the reduced section bearing against said face, a recessed nipple member having spirally disposed grooves in its surface and having threaded engagement with the reduced section so as to provide outward and inward adjustments, and a cap on the head engaging the nipple so as to lock the same in its adjusted position, said cap forming inner and outer chambers with the recessed nipple member and spiral passages between the chambers, said ring forming one wall of the inner chamber and having small spaced communications between the channel and inner chamber.

In testimony whereof, I affix my signature.
PHILIP S. CASE.
